UNITED STATES PATENT OFFICE.

FRED A. PUTNAM, OF KEENE, NEW HAMPSHIRE, ASSIGNOR TO MARKEM MACHINE COMPANY, OF KEENE, NEW HAMPSHIRE, A CORPORATION OF MASSACHUSETTS.

TYPE ELEMENT FOR MARKING MACHINES.

Application filed July 23, 1925. Serial No. 45,539.

This invention relates to marking or printing machines and particularly to those machines which employ a type chase that is made with one or more slotted bars to hold the type. A type chase having this construction is illustrated in co-pending application Serial No. 698,869, filed March 13th, 1924, jointly by myself and Carl E. Putnam. In the type chase shown in said application Serial No. 698,869, each type element is made with a body portion of a size to be received in the type-receiving slot and with shoulders which rest on the top edge of the slotted type-supporting bar and which support the type in proper position.

In order that type of this character may always function properly and be properly lined up when inserted in the slot it is necessary that the supporting shoulders of the type which rest on the top edge of the bar should be of a character to withstand any wear to which the type may be subjected and to also withstand any distortion due to any pressure or strain to which the type is subjected in the printing operation.

Where each type element is a shouldered element it is necessary to make the type element of some relatively hard material such for instance as brass. To make type out of such hard material is a rather expensive operation because the type characters have to be cut on the end of the type elements.

It is one purpose of my present invention to provide novel type members which may be used in a type chase such as described in the above-mentioned co-pending application and which can be manufactured for considerably less than the type members illustrated in said co-pending application.

In accordance with my present invention I use ordinary printer's type, which, as is well known, are made of relatively soft metal and are relatively inexpensive to purchase, and I provide for supporting the type by using type-supporting means which are associated either with each individual type or with groups of type. The supporting means which is associated with each type or group of type is provided with shoulders of relatively hard material arranged to rest on the top edge of the type-supporting bars.

The type-supporting means which I employ can be inexpensively made and when each type or group of type have such type-

supporting means associated therewith a type element is provided having the printing portion thereof made of type metal and having the supporting shoulders which rest on the supporting bars made of relatively hard material which is adapted to resist any wear or deformation resulting from the use of the type.

In order to give an understanding of my invention I have illustrated in the drawings a selected embodiment thereof which will now be described after which the novel features will be pointed out in the appended claims.

Fig. 1 is a top plan view of a type chase having my improved type members supported therein;

Fig. 2 is an enlarged sectional view on the line 2—2, Fig. 1, the type element being shown in elevation;

Fig. 3 is a transverse sectional view on the line 3—3, Fig. 1, showing the type chase as mounted in a printing head;

Fig. 4 is a perspective view of an ordinary printer's type;

Fig. 5 shows said type with holes drilled in it for the attachment of the supporting means;

Fig. 6 is a perspective view of one of the supporting means;

Fig. 7 is a perspective view of one of the type members;

Fig. 8 is a section on the line 8—8, Fig. 7.

The type chase herein illustrated and which is similar to that shown in co-pending application Serial No. 698,869, comprises a frame 1 having a plurality of slotted type-supporting bars 2, the type being inserted in the slot 3 thereof. Each type-supporting bar is shown as formed from two spaced strips 4 of metal which are connected together at their ends, the space between the strips forming the slot 3.

This type chase is designed to be used with type members which have a shank portion extending through the slot 3 and also shoulders to rest on top of the strips 4. In accordance with my present invention each type member is made up of one or more ordinary printer's type such as indicated at 5 and which are made of type metal and are of uniform dimension throughout their length, and type-supporting means which is provided with shoulders of material harder than the type and adapted to rest on top of 110

the strips 4. Each individual type may have the type-supporting means of this character associated therewith or a plurality of type such as would be used for printing a word 5 may be grouped together and have the type-supporting means associated therewith. This type-supporting means which has the shoulders of relatively hard material compared with the material of the type, may be 10 made in various ways without departing from the invention, the principal thing being that the type supporting means associated with each type unit, whether the unit is in the form of an individual type or in the 15 form of a group of type, should have the shoulders of hard material to rest on top of the strips.

One convenient form of type-supporting means is that herein shown which is in the 20 form of plates 6 and when this embodiment of the invention is used I will preferably employ two plates 6 for each type unit. Each plate 6 has a main portion of a width equal to that of the type 5 and has a wider upper portion which forms the shoulders 7 to rest 25 on top of the strips 4. These plates 6 will preferably be made of some material harder than the type metal so that the shoulders 7 will be of material harder than the type 30 metal.

The type units may be made up by providing each individual type with the supporting means or by taking a group of type such as shown in Fig. 7 and associating with 35 said group the supporting means. Where the supporting means is in the form of two plates these two plates will preferably be placed on opposite sides of the individual type or assembled type and may be secured 40 to the type in any appropriate way. One convenient way is to drill holes 8 in the type as shown in Fig. 5, which will be aligned with holes 9 formed in the supporting plates 6 and then to unite the plates and the type 45 by means of rivets 10 inserted through the aligned slots as seen best in Figs. 7 and 8, the rivets preferably being headed over at their ends as shown at 11.

By using type-supporting means made of 50 material which is sufficiently hard, the shoulders 7 will not wear or become distorted through continued use. This will ensure that the type will always be properly lined up when they are inserted into the slots 3.

The type metal of which the ordinary 55 printer's type 5 is made is so soft that if it were cast with the shoulders said shoulders would not be strong enough to withstand the abuse of continued use, but by means of 60 my invention it is possible to take ordinary printer's type and provide the same with shoulders 7 of a sufficient degree of hardness to withstand any wear or strain to which the type is subjected in use.

65 The type chase herein shown is capable of

being removed from the printing head and the type members may be loaded into it from the upper side by simply dropping the type members into the slots. The shoulders 7 of the relatively hard supporting plates will 70 ensure the accurate aligning up of the type.

Where the printed impression is to contain words which are spaced considerably from each other, as would be the case on a label for a shoe box for instance, (Fig. 1 illustrating an arrangement of type which would print such a label), the type members will be positioned longitudinally of the slotted bars by means of positioning members 11 which are clamped to the bars. So 80 far as the present invention is concerned, however, these type blocks may be retained in position in the bars in any suitable way.

In Fig. 3 the type chase 1 with the type members therein is shown as secured to the 85 under side of a head 12, said chase having lips 13 which co-operate with other lips 14 formed on the head 12 to retain the chase in position. One of the lips 14 is shown as carried on a swinging member 15 so as to 90 provide for the removal of the type chase or its insertion into place.

The under face 16 of the head 12 engages the upper ends of the type members and holds them firmly in position against the 95 strips 4.

It will be understood, of course, that, if desired, each type member 5 may be provided with one or more supporting plates 6 but where the type is to be used for printing shoe labels that use a certain number of selected words indicative of the style, size and price of the shoe I propose to assemble the type 5 to form these words and then to make a type block such as shown in Fig. 7 100 for each word. It will also be understood that while I have herein illustrated type-supporting means having hardened shoulders 7 in the form of plates 6 yet the invention is not necessarily limited to this particular construction and the shape of the type-supporting means with the hardened shoulders may be varied without departing from 105 the invention.

I claim:

1. A type member for use with a type chase having a slotted type-holding bar, said type member comprising printer's type adapted to be received in the slot of the type-holding bar, and type-supporting means associated with the type and having portions to rest on top of the bar, said portions being of harder material than the type. 120

2. A type member for use with a type chase having a slotted type-supporting bar, said member comprising a plurality of printer's type adapted to be received in the slot of the bar, two supporting plates between which the type are received, and means for rigidly connecting the type and 130

the plates to form a type block, said plates being of harder material than the type and having shoulders to rest on the top of the type-supporting bars.

5 3. A type member for use with a type chase having a slotted type-supporting bar, said member comprising printer's type, two supporting plates between which the type is received and rivets uniting the type and 10 plates, said plates being of material harder than the type and having shoulders to rest on the top of the type-supporting bar.

15 4. The combination with a type chase having slotted type-holding bars, of type members in said slots, each type member comprising printer's type adapted to be received in the slot and supporting means secured to the type and provided with shoulders to rest on the top of the bar and position 20 the type in the slot, said shoulders be-

ing of material sufficiently harder than that of the type to withstand wear due to use.

5. The combination with a type chase having slotted type-holding bars, of type members received in said slots, each type member 25 being composed of printer's type and supporting plates secured thereto and provided with shoulders for engagement with the top of the type-supporting bar and by which the type member is positioned.

6. A type member comprising printer's type and a supporting means secured to the type and provided with shoulders on which the type member may be supported in a type-chase, the shoulders of said supporting 35 means being of harder material than the type.

In testimony whereof, I have signed my name to this specification.

FRED A. PUTNAM.
